WRAPPING MACHINE FOR ARTICLES OF
VARYING SIZES

Robert J. Beutel, Brooklyn, N. Y., assignor to
American Machine and Foundry Company, a
corporation of New Jersey

Application May 28, 1946, Serial No. 672,786

59 Claims. (Cl. 53—15)

1

This invention relates to wrapping machines and more particularly to wrapping machines of a type which can accommodate a wide range of articles varying considerably in length, width and height.

In a wrapping machine it is always desirable to be able to control the web feeding mechanism and also the mechanism which handles the cut sheet of wrapper, such as paper, wax paper, "cellophane" and other types of wrapping material, in such a way that the position of the laps along the bottom seam of each package is properly located and also a minimum of wrapper is used in the formation of satisfactory packages.

According to the present invention, I have provided a machine in which it is possible to obtain the above desired results, and at the same time increase the efficiency of the machine, especially in connection with the web feeding, cutting and wrapper sheet handling mechanism which form parts of the coordinated wrapping machine structure.

The web feeding mechanism consists of two web feeding devices: One device is mounted on the lifter table which transfers an article and a wrapper from an article receiving station to an article delivery station at a different elevation and wherein each article so delivered is partially enwrapped in the wrapper sheet. The second web feeding device, which is termed an auxiliary web feeding mechanism coacts with the main web feeding device on the lifter table and pulls web from a supply reel or roll during a considerable portion of each operating cycle of the machine. In this manner the main web feeding mechanism on the lifter table, which can be adjusted to feed a desired length of wrapping material according to size of article to be wrapped, can feed a maximum length of material to the wrapper holding and repositioning mechanism in a minimum of time only during a minor portion of each cycle of the machine. This is because when the lifter table moves to its article receiving station, wrapping material which has been pulled over a vertically movable slack roller from the supply roll by the main and auxiliary feed mechanisms, is paid out freely between the rollers on the lifter table but is not positively fed by these rollers at this time. As soon as this slack roller moves upwardly during the operation of the main feed mechanism away from a control device which controls the operation of the auxiliary feed mechanism, additional wrapping material is fed by the auxiliary feed from the source of supply. This continues until a sufficient amount of wrap-

2

ping material has been fed or made available for the next feeding operation of the main web feeding mechanism on the lifter table during the next feeding cycle of operation of the wrapping machine. Hence, the auxiliary wrapping material feeding mechanism operates over a major portion of each machine cycle.

As a result of the above noted method of feeding wrapping material, if a wax paper is fed, accumulation of wax on the feed rollers is materially decreased because of the substantial elimination of slippage in starting the feed of wrapping material from the relatively heavy supply roll. This arrangement also reduces wrapping material web breakage, and as mentioned above, makes possible the feed by the main feeding mechanism on the lifter table of a predetermined length of web in a minimum of time. Furthermore, the only positive feeding operation of the main web feeding mechanism on the lifter table takes place at the time the lifter table is at the delivery station.

The downward motion of the lifter table to article receiving positions results in a draping 25 of the web of wrapping material previously pulled from the supply roll, which passes freely between the feed rollers on the lifter table in the path of travel of the next article to be wrapped.

I have also found that a more efficient cut can 30 be made with a minimum of wrapping material tearing if the web is held under considerable tension between the clamping rollers and the feeding mechanism on the lifter table. For that reason these mechanisms are designed to maintain the web taut when a sheet is to be severed from the web.

It happens rather frequently that articles to 35 be wrapped, such as loaves of bread, may be over-proofed or vary in circumferential measurements. Therefore, in order to insure that the inner and outer laps of the wrapper adjacent the bottom of a wrapped loaf of bread will be properly positioned, I have provided a repositioning mechanism which operates after each wrapper sheet 40 has been cut from the web of wrapping material supply to relocate the sheet and position it in such a manner that proper inner and outer laps will be formed along the bottom of each package. I have also provided means for making suitable 45 adjustments from time to time in order to cover a wide range of article sizes.

The invention also consists in the provision of 50 controlled lifting mechanism which operates to lift the wrapper clamping rollers which hold the upper end of a draped wrapper in order to gradu-

ally release the pressure on the upper supported end of a wrapper sheet and thereby minimize the crushing effect of a wrapper relative to a soft article to be wrapped, such as a loaf of bread. This mechanism also provides means for making tight or loose wrapped packages. Since means are provided for adjusting the operation of the clamping rollers, a wide range of tight-loose wrapped packages is provided.

It is an object of my invention, therefore, to provide an improved bread wrapping machine having wrapper feeding mechanism carried by the article lifter table which is responsible for a more efficient feeding and accurate feeding of wrapper material.

It is a further object of my invention to provide a wrapping machine having a mechanism which supports and holds a portion of a wrapper draped in the path of travel of an article to be wrapped onto an article lifter table and which mechanism is operated to reposition the wrapper relative to the article to be wrapped in such a manner that those portions of the wrapper which form the overlaps of the final package can be positioned with considerable accuracy prior to the engagement of the wrapper sheet by the article to be wrapped.

The invention also consists in the provision of a no-article, no-wrapper control mechanism forming an adjunct to the web feeding mechanism which prevents the operation of the main web feeding mechanism in the event that an article is not present to receive a wrapper. In this manner waste and breakage and jamming due to uncontrolled wrapper feed are eliminated.

It is a further object of the invention to provide a wrapper sheet control which controls the tension of a wrapper being encircled about an article being wrapped in accordance with whether it is desired to produce a tightly or loosely wrapped package.

The invention also consists in the provision of an improved type of article delivery conveyor forming a part of the wrapping machine in which means are provided for adjusting the speed of the delivery belts in order to accommodate over-size articles and small articles with equal satisfaction. In this manner adequate time for cooling heated seals is provided for all sizes of articles passing through and out of the machine.

It is a further object of my invention to provide a web feeding mechanism for a wrapping machine wherein web feeding rollers are mounted on the article lifter table of the wrapping machine which are normally set into operation at a predetermined time during each cycle of the machine in order to advance a predetermined amount of wrapping material to web clamping mechanism.

It is a further object of my invention to provide an auxiliary web feeding mechanism operative in proper timed relation with the operation of the main web feeding mechanism, which auxiliary mechanism operates over a longer period of time during each cycle of the machine to pull paper from a source of supply, and make available such wrapping material for feeding by the main web feeding mechanism with a minimum of accumulation of wax, if wax paper is fed, and with a minimum of breakage with respect to all types of wrappers being passed through the machine.

The invention also consists in the provision of a control device which is operative to displace a portion of a wrapper out of the path of the ad-

vancing end of a succeeding wrapper sheet as it is being fed in order to prevent obstructions and jams in the operation of the machine and increase the general over-all efficiency thereof.

Other objects of my invention will be set forth in the following description and drawings which illustrate preferred embodiments thereof, it being understood that the above statement of the objects of my invention is intended generally to explain the same without limiting it in any manner.

In the accompanying drawings which illustrate a preferred embodiment of the invention and form a part of this specification, and wherein the several reference characters designate the same or like elements:

Figure 1 is a side view of a portion of the improved wrapping machine;

Figure 2 is an enlarged side view, partly in cross-section, showing the positively driven feed rollers on the lifter table and the lap adjustment and knife mechanism;

Figure 3 is a front view taken from line 3-3 of Figure 1 showing the auxiliary paper feeding device;

Figure 4 is a front view taken from line 4-4 of Figure 1 illustrating the positive feeding rollers and also the lap adjusting feed rollers;

Figure 5 is a front view taken from line 5-5 of Figure 1 showing the mounting of the knife, lap adjustment drive and looper arm, also included is the main cam shaft of the machine and coacting members;

Figure 6 is a plan view taken from line 6-6 of Figure 1 of the lap adjusting rollers and associated parts;

Figure 7 is a plan view taken from line 7-7 of Figure 1 showing the variable speed drive for the article take-off conveyor;

Figure 8 is a side view of Figure 7;

Figure 9 is a detail view of the clutch throw-out mechanism employed to disengage the drive of the feed rollers on the lifter table;

Figure 10 is a side view taken from line 10-10 of Figure 3 of the auxiliary paper feed control unit;

Figure 11 is a plan view of Figure 10;

Figure 12 is an enlarged detail view of the lap adjusting driving means; and

Figure 13 is a front view of Figure 12.

Referring to Figures 1 and 5, the main cam shaft 20 of the wrapping machine is provided with a gear 21 meshing with a pinion 22 mounted on a shaft 23. Shaft 23 is also provided with a pulley 24 over which runs a driven belt 25 receiving motion from a pulley (not shown) preferably of a variable type and a suitable source of power. Shaft 20 is supported by side frames 26 and 27. The front end of the frames 26 and 27 are spaced by frame 28; the rear ends of frames 26 and 27 are spaced by a tie frame 30. Shaft 23 has one end supported in a bearing of frame 26; its other end is supported in a bearing 31 in bracket 32 attached to tie frame 30.

On cam shaft 20 is mounted a crank arm 33 (Figures 1, 10 and 11) carrying a roller 34 running in a track 35 in a gear segment 36 loosely mounted on a stud 37 supported in side frame 27. A collar 38 provides means for retaining segment 36 on stud 37. Segment 36 meshes with gear 40 loosely mounted on a stationary stud 42 carried by side frame 27. Gear 40, by suitable means described hereinafter, imparts motion to a sprocket 44 also loosely mounted on stud 42. Sprocket 44 drives a chain 46 running over a

sprocket 48 (Figures 1 and 3) loosely mounted on a stud 50 secured to frame 27. Sprocket 48 drives a gear 52. The hubs of sprocket 48 and gear 52 are formed to provide a clutch 54. Gear 52 in turn drives gear 56 attached on the end of shaft 58 carrying a feed roller 60. Gear 62 also secured to shaft 58 meshes with a gear 64 driving shaft 66 having attached thereto a plurality of spaced feed rollers 68. The ends of shaft 66 are carried by bracket arms 70 pivotally mounted on a cross shaft 72 supported by side frames 26 and 27. The end of each bracket 70 is provided with an ear 74 supporting a post 76 to which is secured one end of a spring 78 connecting to a post 80 mounted in side frames 26, 27 of the machine. Springs 78 are provided to normally hold feed rollers 60 and 68 in web feeding engagement.

Stationary stud shaft 42 (Figures 10 and 11) supports a loosely mounted ratchet wheel 82 and a second ratchet wheel 84 which is secured by screws 86 to sprocket 44, mentioned hereinabove. Gear 40 supports a stud 88 carrying a pivotally mounted arm 90 which at its free end mounts a roller 92 adapted to engage a depressed arc shaped seat 94 formed in the outer periphery of ratchet wheel 82. Arm 90 is also provided with a tooth 96 preferably formed integrally therewith adapted to engage the teeth of ratchet wheel 84, and thus drive ratchet wheel 84 and sprocket 44. A spring 98 having one end anchored to a post 100 fixed to gear 40, and its other end anchored to a post 102 in arm 90 tends normally to hold roller 92 in engagement with its seat 94 in ratchet wheel 82. As seen in Figure 10, a pawl 104 engages a tooth of ratchet wheel 82 thereby preventing it from turning. Thus, when gear segment 36 turns in a counterclockwise direction it drives gear 40 in a clockwise direction causing roller 92 to be disengaged from seat 94 thereby moving tooth 96 out of engagement with a tooth on ratchet 84 and stopping the rotation of ratchet 84 and sprocket 44. When this occurs, roller 92 rides first upon the outer smooth periphery 106 of ratchet 82, and then over the toothed portion of ratchet wheel 82 holding the tooth 96 of arm 90 out of engagement with the teeth of ratchet 84.

It has been found that approximately 210° travel of sprocket 44 is ample to feed the maximum amount of wrapping material, such as waxed paper or regenerated cellulose required to envelop packages within the range of the machine, although obviously the amount of travel of sprocket 44 can be more or less if desired. To prevent an overrun of paper being unwound from reel R, a stop pin 108 is secured in and projects from stationary shaft 42, and so positioned that it registers with the zero or starting position of the feeding cycle of segment 36 and gear 40. Pin 108 engages in an arcuate groove 110 formed in ratchet wheel 82, the groove being of a depth sufficient to clear the diameter of pin 108. It will be seen that when the ratchet 82 rotates its maximum travel, step 112 at the end of groove 110 will engage the pin 108 and interrupt the drive of sprocket 44. On the return cycle of gear 40, roller 92 engages seat 94 and carries the ratchet 82 back to its starting position, the same being stopped by the engagement of step 114 with pin 108.

Pawl 104 is loose on a stud 116 (Figures 10 and 11) which fits into an aperture 118 provided in the end of a stud 120 extending from side frame 27 of the machine. Pawl 104 is operated by a link 122 (Figures 1 and 3) which

connects to a head 124 at the end of cross shaft 126 rotatably supported in frames 26, 27. Shaft 126 carries spaced arms 128 provided with lugs 129 formed integrally therein which engage protruding shouldered ends 130 of cylindrical plugs 132 inserted into the ends of hollow floating or slack roller 134 and mounted to travel up and down in substantially vertical tracks 136 formed by spaced guide bars 138 fastened to tie frame 28 extending transversely of the machine and secured to side frames 26, 27. When this roller 134 is in "down" position (as shown in Figures 1 and 3), arms 128 are depressed causing link 122 to move pawl 104 into engagement with ratchet wheel 82 and stop the feed of wrapper web from reel R.

The web of wrapping material W unwound from reel R is threaded between rollers 60 and 68 and around floating roller 134 upward over a guide roller 140 supported by the side frames 26, 27 of the machine, and between driven feed rollers 142 and 144 supported on and carried by the lifter table of the machine, designated generally as 146. Roller 142 is provided with a plurality of spaced peripheral grooves 143 in which are seated stripper fingers 536, described more in detail hereinabove. When feed rollers 142 and 144 are driven, they pull slack wrapping material previously fed by rollers 60, 68, floating roller 134 is lifted upward thereby permitting arms 128 to ascend and move pawl 104 from engagement with its ratchet 82. A counterweight 148 adjustably mounted on rod 149 secured to head 124 acts to return arms 128 to their "up" position in readiness to again be engaged by ends 130 of roller 134 as it descends. When this takes place, pawl 104 is disengaged from ratchet 82 and the web feeding mechanism, described hereinabove, is made operative to feed additional paper. A spring 150 on rod 122 positioned between a collar 152 on rod 122 and a cut-out portion 154 on pawl 104 is provided to take care of any overrun of the rod 122.

Feed rollers 142 and 144 on lifter table 146, previously mentioned, are intermittently driven from a cam 156 secured to cam shaft 20. Cam 156 is provided with a suitable track 157 tracked by a cam follower 158 (Figures 1 and 3) carried at the upper end of a cam lever 160 fulcrumed on a stud 162 supported by frame 26. The lower curved arm 164 of lever 160 is provided with an arcuate slot 166 engaging a stud 168 of a connecting rod 170 which is connected to arm 172 secured at one end of a cross shaft 174 supported by side frames 26 and 27. To the opposite end of shaft 174 is fastened a gear segment 176 meshing with a pinion 178 loose on a stud 180 secured in frame 27 of the machine. Pinion 178 is attached to a sprocket 182 also free on stud 180, sprocket 182 being retained on stud 180 by collar 184. Arcuate slot 166 in arm 164 provides for an adjustment of rod 170 in order to increase or decrease the travel of gear segment 176, and consequently permit increasing or decreasing the amount of wrapping material fed. When the desired position is determined to accommodate the article being wrapped, rod 170 is locked in place by a lock nut 186. If desired, a graduated scale may be formed on arm 164 adjacent slot 166 to permit rapid adjustment of rod 170 according to length of wrapper needed.

Feed roller 142, which is mounted on shaft 192, is driven in proper timed relation by sprocket 182 through chain 188 running on sprocket 190 loosely mounted on shaft 192. Chain 188 also runs upon an idler sprocket 194 mounted on stud 196

carried by a lug 198 on side frame 27. Feed rollers 142 and 144 do not operate until lifter table 146 arrives in its "up" position (shown in dotted lines in Figure 1). Lifter table 146 is moved between an article receiving station and an article delivery station by means of a cam 200 (Figure 5) having a track 202 tracked by cam follower 204 mounted on cam lever 206 (Figure 1) fulcrumed on a cross shaft 208 supported by the side frames 26, 27 of the machine.

The opposite end of lever 206 is forked at 210 and pivotally connected to a head 212 having a threaded connecting member adjustably secured to a supporting unit 216 (see Figure 5). It is highly desirable to maintain the weight of the lifter table and its associated moving parts at a minimum in order to minimize vibrations and shock, especially at the end of the lifter table stroke at the receiving and delivery stations thereof. In order to obtain this result without sacrificing strength and long use, and in order to increase the efficiency of the lifter table mechanism, unit 216 which forms a part of the lifter table structure is formed of hollow tubes 218, 220 extending upwardly in diverging relationship from their point of connection with unit 210 and a transverse stiffener tube 222 which is connected to tubes 218, 220 together with angle pieces 224, 226 welded or otherwise secured together to form a frame connected by screws 227 to lug 228 situated at each end of the lifter table frame 230. The several tubes mentioned preferably are made of relatively light steel and provide a maximum of strength with a minimum of weight.

Studs 232 extending outwardly at each side of frame 230 (Figure 4) engage blocks 234 mounted for sliding up and down reciprocatory motion on substantially vertical stationary bars 236. A bar 236 is attached to each of the side frames 26, 27 (as shown in Figure 4). The lower ends of bars 236 are attached to lugs on side frames 26 and 27 by screws 231. The upper ends are attached in a similar manner by screws 239. In order to assure smooth functioning of lifter table 146 in its travel between its upper and lower limits or between article receiving and article delivery station, it is preferred to employ a spring 238 which is stretched between a lug 246 on cam lever 206 and a depending lug 242 on a bridge 244, described more in detail hereinafter.

Referring to Figures 1 and 2, when the lifter table 146 is in its "up" or article delivery position (as shown in dotted lines), feed rollers 142 and 144 are set in motion and feed the leading end of the wrapping material onto a shelf 246. At this time a wrapper sheet relocating mechanism, which in the form illustrated consists of an upper set of feed rollers 248, is held in "up" position (shown in dotted lines) by means to be described hereinafter. As table 146 descends, rollers 248 are permitted to descend and engage with a coacting feed roller 250 and thereby clamp the advance portion of the wrapping material W which has been fed onto and along shelf 246. Table 146 on reaching its "down" position (as shown in full lines) has positioned the web W in the path of the incoming article A about to be enveloped.

Articles A to be enveloped, for example loaves of bread, are conveyed over a table 251 at spaced intervals by suitable pusher bars 252 carried by transverse lugs 254 attached to spaced chains 256. A cross shaft 260 supported by the side frames of the machine, carries sprockets 262

driving chains 256. Shaft 260 also carries a sprocket 264 over which runs a chain 266 driven from a sprocket 268 mounted on a stud 270 (see Figures 1 and 5). Sprocket 268 is clutched at 272 to the hub of a pinion 274 driven by a gear 276 fastened to the hub 278 of cam 280 secured to cam shaft 20. Stud 270 is carried by an arm 282 having a bearing 284 fitting loosely on cam shaft 20, the other end of arm 282 is secured to a boss 286 of a lug 288 depending from time frame 30.

Each article to be wrapped is advanced by a flight 252 onto a bridge 244 where it is positioned for delivery onto lifter table 146. An article A having reached a predetermined position on bridge 244 is then engaged by a pusher 290 which conveys the article onto the lifter table 146. Pusher 290 is in a raised position (as shown in dotted lines) when article A, to be wrapped, approaches bridge 244. Pusher 290 is formed by two spaced arms 292 (Figure 5) connected by a bar 294 fastened to arms 292 by screws 296. The center portion of bar 294 is provided with a cutout 298 to give clearance for the pusher in its operation. A plate 300 is attached to bar 294 and carries two protruding pins 302 adapted for locating the pusher plate 304 which engages articles A. Member 300 is provided with an aperture to receive a threaded stud 306 which is attached to plate 304, which is detachably secured to plate 294 by means of a wing nut 308. Each arm 292 pivotally connected to a rod 310 connecting to a forked head 312. One of the heads 312 is pivotally connected to cam lever 314 fulcrumed on cross shaft 316. Lever 314 is provided with a cam follower 318 running in a track 320 of cam 322. The other head 312 is connected to a cam lever 324 fulcrumed on shaft 316. Lever 324 is provided with a cam follower 326 running in a track 328 of cam 280. The above-described mechanism provides the "up" and "down" motion required by pusher 290 to perform its operation.

The reciprocating motion of pusher 290 longitudinally of the machine is effected by means of spaced levers 330 fastened on shaft 316. The upper end of levers 330 are connected by rod 332 to their respective arms 292 (as shown in Figure 1). A cam lever 334 clamped on shaft 316 is equipped with a cam follower 336 running in a suitable track 338 of double cam 200 (as shown in Figure 5). Arms 292 are provided with cam followers 340 and 342 riding in a track 344 in their respective brackets 346 which have depending lugs 348 providing means for attaching the same to the side frames 26, 27 of the machine. Brackets 346 are provided with openings 350 permitting each of the rollers 340 to enter its respective track 344 when arms 292 at the end of its rearward stroke of plunger 350 descend from their "up" position and locate pusher 290 behind the next article to be delivered onto the lifter table. The forward end of each bracket 346 has a cut-out portion 352 which permits the rollers 340 to be lifted from the track at the end of the forward stroke of pusher 290 and ascend to clear the oncoming article being advanced by flights 252 towards bridge 244.

Shortly before an article A being conveyed by pusher 290 onto lifter table 146 engages the hanging wrapping material web W, supported between rollers 248, 250 and rollers 142, 144 on lifter table 146, a knife 354 (Figure 2) severs the wrapper underlying the U-shaped ledger block 356 mounted on the underside of lifter table 146.

Upon the completion of the web severing, lap adjusting rollers 248 and 250 receive motion, by means to be presently described, and according to size of article being wrapped, and operating adjustments previously made, will move the sheet upwardly, advance the cut sheet along table 146, and thereby reposition the sheet for proper engagement by the article to be wrapped. The amount of movement of the cut sheet is governed by the position of an adjustable cam piece provided to disengage a pawl and ratchet mechanism which drives roller 250. This feature permits means for varying the position of the final under lap of the wrapper in relation with the article. If a design is printed on the wrapper sheet, this mechanism makes it possible to adjust for the desired position of the printed matter relative to an article to be wrapped.

As mentioned hereinabove, it is extremely desirable that the draped wrapper web, supported by the clamping rollers 248, 250 and extending beneath guide rollers 357 mounted on lifter table 146 and between feed rollers 142, 144, be held as taut as possible in order to obtain the most efficient type of cut, especially in connection with the use of a serrated knife. In order to accomplish this result after the leading end of the wrapper web has been fed by feed rollers 142, 144 between rollers 248, 250, which are separated at that time, lifter table 146 starts to move to article receiving position, and as bumpers 233 travel downwardly therewith, bar 390 moves out of engagement with extension ears 392 of clamping arms 368 whereupon clamping rollers 248 also move down and clamp the leading end portion of the wrapping material web against rollers 250. Also, as table 146 moves down, sprocket chain 188 is held stationary and acts as a rack to turn feed rollers 142, 144 which pay out the wrapper web previously fed by the auxiliary feed rollers 68, 69. When, therefore, lifter table 146 reaches its lower limits of travel at article receiving position a wrapper sheet length of web is draped properly relative to the next article to be wrapped. Since table 146 is so mounted that it inclines downwardly when located at article receiving position, tension is applied to the suspended portion of the wrapper web W.

When pusher 290 advances an article A towards the lifter table 146, a roller 358 (Figure 1) on the pusher rides on a trip bar 360 depressing the same and causing a link 362 to operate a lever 364 and lift a cross bar 366 (see Figures 2 and 6) secured to arms of levers 364, 374 loosely supported by cross shaft 372 (Figure 6). The upward travel of bar 366 raises a plurality of arms 368 (Figure 6) thereby lifting rollers 248 from engagement with feed roller 250. The center arm 370 which is also equipped with a roller 248 retains its position in engagement with roller 250 maintaining a slight clamp on the hanging severed wrapper W. This feature relieves the possibilities of crushing or deforming articles of soft consistency during the enveloping stages. A cross bar 371 is secured to the other arms of levers 364, 374. Arms 368 which are loosely mounted on shaft 372 are provided with U-shaped clips 376 having elongated slots 378 (Figure 2) engaging the bar 366, the ascent of said bar thus lifts the arms 368 against the pressure of flat springs 380 attached to the bottom folding table 382 of the machine. Springs 380 are arranged (as shown in Figure 6) so as to engage each of the arms 368 and also arm 370. Springs 380 normally hold the arms and

their rollers 248 in the "down" or clamping position relative to roller 250.

An article A in approaching lifter table 146 engages the hanging wrapper sheet W and presses it against a back tension plate 384 of conventional design. The continued forward movement of article A pushes plate 384 to a position shown in dotted lines (Figure 2). As a result of the movement of an article with wrapper sheet W onto lifter table 146, the first under-fold of the wrapper is completed and the extending front end portions of the wrapper are folded by tuckers 386 against the ends of article A into flaps I. When article A has been located on lifter table 146, pusher arm 290 is returned a short distance and then gradually lifted to clear the succeeding article A on runway 251 and then moved back to its starting position (shown in dotted lines in Figure 1). During this time the lifter table has moved upwardly on stationary bars 236 to article delivery position where a partially wrapped article is ejected onto table 382.

As shown in Figure 1, trip bar 360 supports an extension 361 adjustably secured thereto by means of a wing nut 363. In this manner extension 361 can be located at the extreme position indicated in full lines in Figure 1 or with the free end thereof closely adjacent the pivot point or connection of link 362 with trip bar 360. Hence, engagement of cam follower 358 with extension 361 of trip bar 360 causes lever 364 to rock and lift a majority of the clamping rollers 248 out of engagement with a wrapper sheet passing over roller 250. It is obvious when this condition prevails that the top portion of a wrapper sheet is supported by a single roller 370 in the path of travel of an article with the wrapper sheet onto lifter table 146. At this time, therefore, a minimum of tension is exerted by the wrapper about the article being wrapped and the resulting packages may be termed loosely wrapped. When, however, extension 361 is adjusted to the left along trip arm 360 (as viewed in Figure 1) an article to be wrapped engages 45 and travels with the wrapper sheet onto lifter table 146, and at the same time the upper portion of the wrapper sheet is held by all of the clamping rollers 248 against roller 250 until cam follower 358 engages extension 361 to rock rollers 248 out of coaction with rollers 250 whereupon the tension in the wrapper is decreased. Due to this operation, the wrapper is applied with greater tension about an article and a relatively tight wrap is obtained. It is obvious that when extension 361 is adjusted to its "tight wrap" limit adjacent pivot 368, the maximum amount of tension is applied to the wrapper about the article which results in the greatest degree of tight wrap package.

The upward travel of table 146 brings bumpers 388 into engagement with the ends of a floating roller 390 (Figures 2 and 6) carrying the same into contact with the extending ears 392 of clamp arm 370 thereby raising roller 248 from engagement with its coacting roller 250. Bumpers 388, which preferably are formed of a shock absorbing material such as rubber, are mounted on projections 389 on the frame of lifter table 146. The continued upward travel of lifter table 146 causes floating roller 390 to engage the extending ears 392 of clamp arms 368 which had been raised previously by bar 366 in the manner described hereinabove.

The ends of floating roller 390 are mounted for movement in spaced U-shaped guide mem-

bers 391, one of which is attached to a bracket 393 fixed to the respective side frames 26 and 27. The flanges of each guide member 391 have a series of spaced holes 395 through which is inserted a pin extending through a stop piece 397 adjustably mounted in each of guide members 391. In this manner stop piece 397 can be adjusted to arrest the descent of roller 390 in any desired position governed by the size of article to be wrapped.

Clamp arms 368 and 370 now being in raised position, the end portion of wrapper sheet is no longer clamped or held against the web W on shelf 246 and is free to be moved to complete the enveloping of the article being wrapped. With the lifter table in its uppermost position (as shown in dotted lines in Figures 1 and 2) the wrapper sheet has been folded almost completely about the article and spaced top end folder plates 394 located in the path of upward travel of articles A on lifter table 146 have formed end flaps II. The partially wrapped article still located on lifter table 146 is in a position to be acted upon by a top conveyor flight 488 which propels the article from the lifter table into the foldway.

Wrapper sheets W are cut from the web supply by knife 354 which is fastened to a transverse bar 396 carried by spaced arms 398 fixed to a pivot shaft 400 supported by the side frames 26, 27 of the machine. A lever 402 fast on the shaft 400 is adjustably connected to one end of link 404, the other end of which is adjustably connected to arm 406 of a cam lever 407 fulcrumed on stud 42 (Figures 2 and 5). The other arm 408 of cam lever 407 carries a cam follower 410 running in a track 412 in cam 414 which is part of cam 280. When the cam follower 410 engages the high portion 416 of the cam track 412, motion is imparted to arms 398 raising knife 354 which with the aid of ledger block 356 on the underside of lifter table 146 severs a wrapper sheet W from the supply issuing from the reel R.

Feed roller 250 preferably is hollow, in order to cut down weight, and insure straight line engagement with upper feed rollers 248. One end of roller 250 (Figure 4) is secured to the larger section of a shouldered stud 418: its opposite end is mounted in a similar manner on a shouldered stud 420. Intermittent motion is imparted to roller 250 by means of a pawl and ratchet mechanism. A suitable driving mechanism consists of a combined gear 422 and arm 424 loose on stud 418 which is provided with a pawl 426 adapted to engage a ratchet wheel 428 secured on stud 418 (as shown in Figures 12 and 13 in enlarged scale). Pawl 426 has a tooth 430 engaging the teeth 432 of ratchet wheel 428. A roller 434 on pawl arm 426 is provided to disengage pawl tooth 430 from a ratchet tooth 432 when it encounters the cam surface 436 of an adjustable cam member 438 located adjacent the face of side frame 26 and provided with a shouldered portion 440 fitting loosely in an aperture of frame 26. Shouldered portion 440 serves as a bearing for stud 418 and also serves to support an adjustable bracket 442, the latter being secured thereto by means of key 444. Bracket 442 is provided with an arcuate slot 446 whereby the position of the cam surface 436 may be shifted in order to increase or decrease the feeding cycle of roller 250. When the desired position of the cam 436 is obtained, it is retained in place by tightening a thumb screw 448. Pawl 426 is normally held in engagement with its ratchet wheel by spring 450 having one end

anchored to a post 452 in the pawl and its other end anchored to a post 454 in arm 424.

Stud 420 has a threaded portion for a knurled nut 421 providing means for tensioning a spring 423 which is arrested between the nut and a disk 425 encircling stud 420 and urged by spring 423 against a fiber disk 427 on stud 420. A similar fiber disk 429 at the opposite end of roller 250 is placed between the hub of ratchet 428 and the flange of cam member 438. Fiber disks 427 and 429 are provided to serve as an additional clamp for roller 250.

Gear 422 receives intermittent motion from a gear segment 456 mounted on a stud 458 carried by the side frame 26 of the machine. Gear segment 456 is provided with an arm 460 supporting one end of a link 462 adjustably connected to arm 464 fixed on shaft 400. Shaft 400 also supports loosely mounted hubs 466 which together with vertically extending hollow tubes 468 and a cross tube 470 forms a looper arm 472 adapted to engage the trailing end W' of the wrapper sheet W depending from a partially wrapped article on lifter table 146 (see Figure 2). Arm 472 receives motion by means presently to be described, and travels forwardly to engage the free hanging end of the wrapper web W', which occurs at the time when lifter table 146 is at its upper or raised position and feed rollers 142 and 144 commence to feed a new length of wrapping material onto shelf 246. In this manner, wrapper sheet end W' is moved out of the path of the oncoming end of the wrapper web permitting the same to pass unobstructedly onto the shelf 246.

Arm 472 is actuated by means of adjustabl studs 474 carried in extending ears 476 on lever 402 and arm 464, respectively. Stud 474 of each of the above mentioned members are so positioned as to be in the path of depending tails 478 on each of the hubs 466. Arm 472 is normally retained in its inactive position by means of springs 480 tending to hold the tube 470 against spaced stop members 482 mounted on the underside of foldway table 382. Cam 414 serves to impart the necessary motions required to actuate the knife 354, lap adjusting feed rollers 248 and 250, and looper arm 472. It will be seen that the knife severs the web W when the lifter table 146 is in its "down" position. Therefore, the motion imparted to link 462 at this time causes the gear segment 456 to move in a non-feeding direction. Looper arm 472 remains motionless during this period as its operating studs 476 are moving away from the actuating tails 478. The continued rotation of cam 414 causes the cam follower 410 to engage a high portion of track portion 484 and thereby impart feeding motion to rollers 248 and 250. When this occurs, knife 354 moves downwardly and away from ledger plate 356 and the previously severed sheet; looper arm 472 still remains motionless as the travel of lever 402 and arm 464 is insufficient to cause studs 474 to bear against the move tails 478 of looper arm 472. When cam 414 brings its dipped track portion 486 into engagement with the cam follower 410, this motion causes the studs 474 to engage and bear against tails 478 and impart motion to arm 472 thus moving the hanging end W' of the cut sheet out of the path of the incoming web being fed by the rollers 142 and 144 of lifter table 146 onto and along shelf 246. It will be understood that the table 146 is raised to its "up" position during the elapsed period of time it takes cam 414 to rotate so as to bring cam track portion 486 into engagement with cam follower 410. The movement of

arm 472 causes knife 354 to descend and the motion imparted to segment 456 results in turning pinion 422 idly as the upper set of feed rollers 248 are in their "up" position during this time. When the cam follower 410 again rides in the concentric portion of the track 412, looper arm 472 is returned to its starting position by the springs 480 (as shown in full lines in Figure 2).

When the lifter table 146 is in its "up" position, a partly enveloped article A (mentioned hereinabove) is moved by a pusher 488 and conveyed into the final folding and sealing stations formed by a set of folder plates 490 and 492 of conventional design. The leading edge of plate 490 folds the extending rear side webs of the wrapper against the ends of article A to form end flap III and the extending bottom webs of the wrapper enter the space 498 between the folder plates whereby the final end folds IV of the wrapper are completed. Suitable heaters 496 are provided on members 490 and 492 to seal the end flaps of the wrapper. The final bottom fold of the wrapper is completed prior to the formation of flaps III and IV when the extending web passes over the bottom folder plate 382. A suitable heater 498 is attached to the bottom folder plate 382 to seal the bottom flaps of the wrapper.

Feed roller 142 carried by lifter table 146 preferably is formed from hollow steel or other tubing in order to cut down on weight, and vibration, and to provide a roller having adequate strength and one free from bowing. Referring to Figures 1, 2 and 4, hollow feed roller 142 at one end is attached to the hub of gear 500 on shaft 192. Gear 500 meshes with a gear 502 fastened to a shaft 504 carried by a plurality of spaced arms 506 mounted on a shaft 508 mounted in end frame portions 230 of lifter table 146. Arms 506 at the ends of shaft 504 have projecting arms 507 carrying a cross rod 509 (Figure 2) supporting one end of springs 511 connected to a cross rod 513 of the lifter table frame. Springs 511 tend to normally hold the upper rollers 144 in web feeding engagement with their coacting feed roller 142. Arms 507 when depressed manually provide means for lifting rollers 144 fixed to shaft 504 out of feeding cooperation with roller 142 in order to facilitate threading of the wrapper web.

Gear 509 is provided with a one-direction clutch 510 provided to insure that the web W will remain clamped between the feed rollers 142 and 144 when table 146 moves to its "up" position. The upward motion of table 146 causes the rollers to pull the slack wrapper or floating roller 134 upward. Roller 142 is driven by and in proper timed relationship with the operation of the machine by means of a clutch mechanism, designated generally 513. A toothed clutch member 512 is secured to the other end of roller 142, as by welding, or any other suitable means. Clutch member 512 is adapted to be engaged by a movable toothed member 514 slidably mounted on and secured to the hub of sprocket 198. Each time table 146 arrives at its lowermost position, a finger 516 engages an adjustable stop screw 518 (Figures 2, 4 and 9) and clutch throw-out arm 520 is swung to disengage clutch member 514 from member 512. Finger 516 is attached to a square section 522 of a stud 524 supported in a boss on clutch 514 on throw-out arm 520. Arm 520 is loosely mounted on a stationary stud 526 supported in arms 528 depending from lifter table frame 230. An opening 530 is provided in lifter table frame 230 to allow the necessary

movement of finger 516 for clutching and unclutching members 512, 514. As lifter table 146 approaches its uppermost position (shown in dotted lines in Figure 1), finger 516 strikes 5 against an adjustable stop screw 532 mounted on lever 500, and so adjusted that clutch 513 is thrown in at the proper time as the lifter table 146 moves upwardly in its uppermost position. With clutch parts 512, 514 in engagement, cam 10 actuated gear segment 176 is operated, chain 188 and sprocket 190 on which chain 188 runs, cause feed rollers 142 and 144 to rotate and feed wrapping material W from the supply between a plurality of spaced upper and lower stripper members 534, 536, respectively, which prevent the web 15 passing therebetween from curling about either of rollers 142, 144. This feature is of special value when a waxed material, such as waxed paper is being fed.

20 The advancing end of the web passes over a bridge consisting of a plurality of spaced strips 538 (Figure 6) fastened to a support member 540 mounted on and extending transversely of lifter table 146. A roller 519 on clutch operating arm 520 is engaged by a lock spring 521 mounted on 25 and projecting from lifter table frame 230. Engagement of rollers 519 with one portion or another of spring 521 locks clutch member 514 either in operative or inoperative position relative to clutch member 512 secured to roller 142.

The advancing end of the web then passes 30 over the feed roller 250 beneath rollers 248 which are raised at this time, and onto shelf 246 which preferably consists of a plurality of spaced strips 35 542 (Figure 6) attached to a transverse supporting bar 544, fastened to spaced blocks 546 supported by shaft 372. The upper end of blocks 546 carry the folder plate 382 which makes the 40 final bottom fold, and along which an article being wrapped is moved between folders 490, 492. At the conclusion of the web feeding operation of rollers 142, 144 when a predetermined length of 45 web has been fed from the supply and the leading end portion is on shelf 246, table 146 descends permitting rollers 248 to descend and clamp the web against roller 250. During the descent of 50 table 146, chain 188 is stationary and acts as a rack relative to sprocket 190, therefore, rollers 142 and 144 do not feed additional web but merely pay out web which has been pulled from supply roll R previously and drape it in the path of travel of the next article A to be wrapped.

The pusher plate 488 which conveys a partially wrapped loaf along plate 382 and between folders 55 490, 492 is supported at its opposite ends by arms 548 fixed to each of the spaced conveyor chains 550. Chains 550 pass over driven sprockets 552 secured on a stud 554 and over idler sprockets 556 mounted on a shaft 558. The studs 554 and 60 558 are supported by the side frames 26, 27 of machine. A gear segment 560 mounted on fulcrum stud 562 supported by side frame 26 meshes with a pinion 564 on stud 554. A link 566 is connected to an extension on segment 560 and to a cam lever 568 fulcrumed on stud 162 (Figures 65 1 and 3). Cam lever 568 is provided with a cam follower 570 running in a track 572 of double cam 322 in order to produce a to and fro motion to chains 550.

A no-article, no-wrapper device preferably is incorporated in the infeed conveyor runway to prevent the paper feed from operating when a miss occurs in the flow of articles entering the machine. A satisfactory mechanism for accomplishing this purpose consists of a pivotally

mounted trip finger 514 projecting upwardly into the path of movement of incoming articles. Finger 514 preferably is located midway between side frames 26, 27 in the path of travel of articles into the machine, although it can be located at any other transverse position so long as it is positioned for ready engagement by articles to be wrapped. Finger 514 is mounted on a pivot shaft 516 to which is secured (Figure 1) an actuating arm 518 having connected thereto one end of a link 580 which in turn is connected to an arm 582 of a bell crank lever 583 fulcrumed on a stud 584 on side frame 27. The other arm 586 of bell crank lever 583 (Figures 2 and 3) is pivotally connected to a link 588 connected to an arm 590 fulcrumed on a stud 592 carried by the side frame 27 of the machine. Arm 590 is provided with a downwardly extending stop screw 532, previously mentioned, adapted to couple clutch parts 512, 514 in order to drive rollers 142, 144. During normal operation of the machine, when lifter table 146 ascends and approaches its uppermost position, with an article A, the succeeding article passes over and depresses finger 514 which causes arm 590 to rock and position adjustable set screw 532 in the path of ascending finger 516 which throws in driving clutch 512, 514 of roller 142. When lifter table 146 descends, and finger 516 is moved out of engagement with screw 532, a spring 594 relocates finger 514 in an upright position relative to table 251 through which it projects in readiness to be engaged by a succeeding article moved by a conveyor flight 252 along table 251. Spring 594 is fastened at its ends to posts 596 and 598, the former being supported in arm 586 of bell crank lever 583; the latter being carried by a stationary bar 600 attached to frame 27. Spring 594 in resetting finger 514 causes arm 590 to swing and move stop screw 532 from engagement with stop pin 602 to a position against a stop pin 604. Stop pins 602 and 604 which extend into the path of stop screw 532 on arm 590 are secured to the side frame 27 of the machine.

When a skip occurs in the feeding of the articles, trip finger 514 remains in its upright position holding the stop screw 532 against stop pin 604. Therefore, when lifter table 146 reaches its uppermost position, clutch driving members 512, 514 remain uncoupled since screw 532 is positioned out of the path of clutch reset finger 516. Hence, in this cycle of operations, no wrapper is fed by rollers 142, 144 onto shelf 246. This condition continues until an article being moved along table 251 by a flight 252 of conveyor 256 again engages and trips finger 514 which projects upwardly through an opening in table 251 whereby stop screw 532 is moved into the path of finger 516 for swinging clutch yoke 520 to engage clutch driving members 512, 514.

Any suitable delivery mechanism can be employed for removing wrapped articles from the machine. In the machine illustrated, the take-off or delivery conveying mechanism is equipped with a speed adjusting device which makes it possible to run the conveyor either fast or slow, depending upon the size of articles being wrapped. The range of the machine is such that articles ranging, say from eight and one-half inches down to three inches in width, can be wrapped. In the case of the larger articles, the conveyor mechanism is designed to move the wrapped-sealed packages out of the machine faster than pusher 488 pushes articles being wrapped between the folders. That is, when

package P pushes package P' from between plates 492, the latter is moved forwardly at a relatively high rate of speed by belts 606, 618 as compared with the movement of pusher 488, and is separated from package P. However, if in the case of relatively small articles, such as the normal or average size loaf of bread produced in high production today which is about four inches wide, it is obvious that if the high speed just described were employed, packages would not be satisfactorily spaced on conveyor belt 610 between side belts 606 because this size of article would be moved out of the machine too rapidly without taking full advantage of valuable cooling space available. For this reason I have provided an adjusting device which makes it possible to drive the conveying belts 606, 610 at a second or slow speed when articles with a width of five inches or less are being wrapped. This speed allows more time for cooling the hot end seals of wrapped packages.

Pusher 488 which propels partially wrapped packages from lifter table 146, advances the same onto a bottom folder and supporting plate 382 and between spaced end folders and sealing means 490, 492, as described hereinbefore. Each article moved by pusher 488 is advanced to a position indicated in dotted lines in Figure 1, after which the pusher 488 retreats to the full line position shown in Figure 1 awaiting the delivery of a new article into the range of operation of the pusher by lifter table 146. In known manner, as each partially wrapped article is removed by pusher 488 from lifter table 146, back tension plate 384 is engaged by pusher 488 and moved forwardly to the full line position (indicated in Figure 2) where it remains until the next article moved against a draped wrapper sheet onto lifter table 146 pushes it back to the position shown in dotted lines in Figure 2.

Large wrapped and sealed articles remain at the discharge end of folder plates 492 which permits further heat sealing of the final or bottom end folders IV. Each succeeding package delivered to this position advances the last delivered package so that continued operation of pusher 488 results in a stream of wrapped packages moving from end folders 490, sealers 492 between belts 606 of the take-off conveyor.

The delivery conveyor consists of two spaced endless belts 606 and 608 which may be adjusted to and from each other by suitable conventional means (not shown), and a bottom belt 610 all of which are driven from cam shaft 20 of the machine by means to be described. A sprocket 612 (Figures 1 and 5), secured to cam shaft 20, drives a chain 614 running over a sprocket 616 loosely mounted on a shaft 618 supported in side frames 26, 27. A gear 620 which may be a part of sprocket 616 (as shown in Figures 7 and 8) meshes with a gear 622 mounted on a stud 624 supported in arm 626 of a bell crank lever 625. Gear 622 meshes with gear 628 fast on shaft 630 driving a pulley 632 over which runs one loop of the bottom conveyor belt 610. An arm 660 secured to one end of shaft 618 provides means for disengaging the drive mentioned, and by shifting the position of arm 660 a secondary set of gears is set in motion to drive the conveyor at a reduced or slower speed. This is accomplished by pulling knob 662 of a spring loaded stud 664 and freeing the end of stud 664 from engagement with an aperture 666 in frame 26. The arm 660 thus freed is moved and stud 664 eventually snaps into an aperture 668 also pro-

vided in frame 26. This new position of arm 660 results in the disengagement of the driving gears 622, 628. The swinging of arm 660 causes shaft 618 to swing the bell crank lever 625 and its vertically extending arm 670 carries gear 672 mounted thereon into engagement with gear 674 mounted on shaft 630. The meshing of gears 672 and 674 imparts driving motion to the take-off conveyor at a reduced speed.

The invention above described may be varied in construction within the scope of the claims, for the particular device, selected to illustrate the invention, is but one of many possible concrete embodiments of the same, it is not, therefore, to be restricted to the precise details of the structure shown and described.

What I claim is:

1. In a wrapping machine having an article lifter table adapted to be moved to and from an article receiving station and an article delivery station, web feeding mechanism carried by said lifter table, and means for driving said mechanism to feed a length of wrapping material relative to said table.

2. In a wrapping machine having an article lifter table adapted to be moved to and from an article receiving station, and an article delivery station, web feeding mechanism carried by said lifter table, and means for intermittently driving said mechanism to feed lengths of wrapping material relative to said table.

3. In a wrapping machine having an article lifter table adapted to be moved to and from an article receiving station, and an article delivery station, web feeding mechanism carried by said lifter table, means for intermittently driving said mechanism to feed lengths of wrapping material relative to said table, an auxiliary web feeding mechanism for pulling wrapper material from a source of supply for delivery to said first-named mechanism, and means for incapacitating said auxiliary web feeding mechanism when a predetermined quantity of web has been pulled from said supply.

4. In a wrapping machine having an article lifter table adapted to be moved to and from an article receiving station, and an article delivery station, web feeding mechanism carried by said lifter table, means for intermittently driving said mechanism to feed lengths of wrapping material relative to said table, an auxiliary web feeding mechanism for pulling wrapper material from a source of supply for delivery to said first-named mechanism, means for incapacitating said auxiliary web feeding mechanism when a predetermined quantity of web has been pulled from said supply, and article operated control means for incapacitating said first-named web feeding mechanism.

5. In a wrapping machine having an article lifter table adapted to be moved to and from an article receiving station and an article delivering station, said lifter table comprising an article supporting surface, and a web feeding mechanism mounted on said lifter table, and means for driving said mechanism to feed a length of wrapping material beneath said surface.

6. In a wrapping machine, a lifter table provided with an article supporting surface, web feeding mechanism mounted on said table beneath said surface, mechanism for moving said lifter table to and from an article receiving station and an article delivery station, a web holding device, and means for driving said web feed-

ing mechanism to advance the leading end of a web of wrapping material beneath said surface to said device.

7. In a wrapping machine, a lifter table provided with an article supporting surface, web feeding mechanism carried by said lifter table, said web feeding mechanism including a pair of feed rollers, a web clamping device, means for moving said lifter table to and from an article receiving station and an article delivery station, and means for driving said web feeding rollers to advance the leading end of a web of wrapping material beneath said surface to said device.

8. In a wrapping machine, a lifter table provided with an article supporting surface, web feeding mechanism carried by said lifter table, said web feeding mechanism including a pair of feed rollers, a web clamping device, means for moving said lifter table to and from an article receiving station and an article delivery station, strippers coating with said rollers for preventing said web from adhering to said rollers, and means for driving said web feeding rollers to advance the leading end of a web of wrapping material beneath said surface to said device.

9. In a wrapping machine, a lifter table provided with an article supporting surface, web feeding mechanism carried by said lifter table, said web feeding mechanism including a pair of feed rollers, a web supporting device, means for moving said lifter table to and from an article receiving station and an article delivery station, a web feeding mechanism control, means mounting said control in the path of movement of said lifter table to article delivery position, and an arm carried by said lifter table positioned to engage said control for operating said web feeding mechanism to drive said rollers and to effect the feed of a length of web to said supporting device.

10. In a wrapping machine, a lifter table provided with an article supporting surface, web feeding mechanism carried by said lifter table, said web feeding mechanism including a pair of feed rollers, a web supporting device, means for moving said lifter table to and from an article receiving station and an article delivery station, a web feeding mechanism control, means mounting said control in the path of movement of said lifter table to article delivery position, an arm carried by said lifter table positioned to engage said control for operating said web feeding mechanism to drive said rollers and to effect the feed of a length of web to said supporting device, and means for moving said control out of the path of said arm to incapacitate said mechanism if an article fails to advance into said machine for delivery to said lifter table at said receiving station.

11. In a wrapper machine, a lifter table provided with an article supporting surface, web feeding mechanism carried by said table, said mechanism including a driving roller and a driven roller, a first clutch member mounted on said driving roller, a second clutch member movable into and out of driving engagement with said clutch member, and means operative by movement of said lifter table to an article delivery station for moving said second clutch member into driving relation with said first clutch member to feed a predetermined length of paper relative to said surface.

12. In a wrapping machine, a lifter table provided with an article supporting surface, web feeding mechanism carried by said table, said

19

mechanism including a driving roller and a driven roller, a first clutch member mounted on said driving roller, a second clutch member movable into and out of driving engagement with said first clutch member, means operative by movement of said lifter table to an article delivery station for moving said second clutch member into driving relation with said first clutch member, a sprocket attached to said second clutch member, a sprocket chain running on said sprocket, means for driving said sprocket during a portion of each cycle of said machine when said first and second clutch members are engaged to feed a predetermined length of paper relative to said surface, and means for uncoupling said clutch members when said lifter table moves to an article receiving position.

13. In a wrapping machine having an article lifter table adapted to be moved to and from an article receiving station and an article auxiliary station, web feeding mechanism carried by said lifter table, means for driving said mechanism to feed a length of wrapping material relative to said table, a conveyor for feeding articles to be wrapped into said machine for delivery onto said lifter table, an article detecting device mounted in the path of movement of articles into said machine, and means under control of said device for incapacitating said web feeding mechanism whenever a skip occurs in a succession of articles being fed by said conveyor.

14. In a wrapping machine having an article lifter table adapted to be moved to and from an article receiving station and an article delivery station, web feeding mechanism carried by said lifter table, means for driving said mechanism, and a detector device located adjacent said article delivery station for operating said means to feed a length of web.

15. In a wrapping machine provided with an article lifter table adapted to be moved back and forth between an article receiving and an article delivery station, a web receiving mechanism located adjacent said delivery station, a web feeding device carried by said lifter table, and means for driving said device to feed a length of wrapping material to said mechanism.

16. In a wrapping machine provided with an article lifter table adapted to be moved between an article receiving and an article delivery station, a web receiving mechanism adjacent said delivery station, a web feeding device carried by said lifter table, means for driving said device to feed a length of wrapping material to said mechanism, and means for operating said mechanism to clamp a portion of said wrapper advanced by said device into said mechanism.

17. In a wrapping machine provided with an article lifter table adapted to be moved between an article receiving and an article delivery station, a web receiving shelf adjacent said delivery station, web feeding mechanism carried by said lifter table, means for driving said mechanism to feed a length of wrapping material onto said shelf, paper clamps mounted above said shelf, means for moving said clamps to clamp a portion of said wrapper advanced onto said shelf and hold said wrapper draped in the path of travel of articles onto said lifter table, and means for cutting said draped portion of said wrapper from said web.

18. In a wrapping machine provided with an article lifter table adapted to be moved between an article receiving and an article delivery station, a web receiving shelf adjacent said delivery

20

station, web feeding mechanism carried by said lifter table, means for driving said mechanism to feed to length of wrapping material onto said shelf, means for moving said table to said receiving station and draping a wrapper in the path of travel of an article onto said lifter table, means for cutting said draped portion of said wrapper from said web, and means for repositioning said wrapper sheet prior to the association of an article to be wrapped with said sheet.

19. In a wrapping machine having an article lifter table adapted to be moved to and from an article receiving station and an article delivery station, web feeding mechanism carried by said lifter table, a wrapper receiving shelf located adjacent said article delivery station, means for driving said mechanism when said lifter table is located at said delivery station, clamping means for holding the end of a wrapper web fed by said mechanism upon said shelf, means for lowering said lifter table to drape a predetermined portion of said wrapper web in the path of travel of an article onto said lifter table, means for cutting said draped portion of said web from said supply and thereby providing a wrapper sheet for the next article to be wrapped, and means for actuating said clamping means to relocate said wrapper sheet for proper engagement by said article prior to the movement of said article onto said lifter table.

20. In a wrapping machine, a wrapper support constructed and arranged to support the leading end portion of a stationary cut wrapper sheet, means for holding said leading end portion of said wrapper sheet on said support with the trailing end portion of said wrapper depending therefrom in a substantially vertical plane, web feeding means associated with said last named means, mechanism for driving said last-named means to feed said leading end of said sheet a predetermined distance along said support to relocate said leading end of said sheet thereon and reposition said depending trailing end relative to the path of movement of an article into engagement therewith, means for adjusting said mechanism to control the amount of movement of said leading end of said sheet by said web feeding means along said support, an article conveyor, and means for actuating said conveyor to advance said article into engagement with said relocated sheet.

21. In a wrapping machine of the type provided with an article lifter table movable between article receiving and article delivery station, a wrapper support located between said stations, mechanism for feeding the leading end portion of a web of wrapping material beneath said lifter table and onto said support, mechanism for holding said leading end portion of said wrapping material on said support, said mechanism including a pair of coacting web feeding rollers, means for lowering said lifter table to drape said wrapper web in the path of travel of an article onto said table, means for separating the draped portion of said wrapper web from said supply to form a substantially vertically positioned wrapper sheet, means for driving said pair of rollers to move said leading end portion of said sheet along said support and lift said wrapper sheet and locate the bottom edge thereof in a predetermined position relative to an article to be wrapped, a pusher for pushing an article to be wrapped against said draped repositioned wrapper sheet and onto said lifter table, and means

for operating said pusher subsequent to the operation of said last-named means.

22. In a wrapping machine of the type provided with an article lifter table movable between article receiving and article delivery stations, a wrapper support located between said stations, mechanism for feeding the leading end portion of web of wrapping material beneath said lifter table and onto said support, mechanism for holding said portion of said wrapping material on said support, said mechanism including a pair of coacting upper and lower feeding rollers, means for moving said upper rollers towards said lower rollers to engage and hold said portion of said web, means for lowering said table to drape said web in the path of travel of an article onto said table, means for separating the draped portion of said web from said supply to form a wrapper sheet, means for driving said rollers to lift said sheet, means for moving some of said upper rollers out of holding engagement with said sheet to minimize the constrictive force applied to an article advanced with said sheet onto said table, and means for subsequently moving the remainder of said upper rollers out of engagement with said sheet as said lifter table approaches said delivery station.

23. In a wrapping machine of the type provided with an article lifter table movable between article receiving and article delivery stations, a wrapper support located between said stations, mechanism for feeding the leading end portion of web of wrapping material beneath said lifter table and onto said support, mechanism for holding said portion of said wrapping material on said support, said mechanism including a pair of coacting upper and lower feeding rollers, means for moving said upper rollers towards said lower rollers to engage and hold said portion of said web, means for lowering said table to drape said web in the path of travel of an article onto said table, means for separating the draped portion of said web from said supply to form a wrapper sheet, means for driving said rollers to lift said sheet, means for moving some of said upper rollers out of holding engagement with said sheet to minimize the constrictive force applied to an article advanced with said sheet onto said table, and means for subsequently moving the remainder of said upper rollers out of engagement with said sheet as said lifter table approaches said delivery station, and means operative when said lifter table is located at said delivery station for displacing said portion of said wrapper sheet out of the path of travel of said leading end of said web.

24. In a wrapping machine of the type provided with a lifter table adapted to move between an article receiving and an article delivering station, means for supporting a wrapper draped in the path of movement of an article onto said lifter table, means for supporting a portion of said draped wrapper sheet above said article receiving station, said last-named means including web feeding mechanism for moving said wrapper sheet upwardly relative to said lifter table when the latter is at said article receiving station to properly locate the bottom portion of said wrapper sheet for wrapping about said article, and mechanism for operating said last-named means prior to the engagement of an article with said wrapper sheet.

25. In a wrapping machine of the type having an article lifter table and means for moving said table between an article receiving station and an article delivery station, a wrapper supporting shelf located between said stations and adjacent

the path of travel of said table, a driving feed roller mounted adjacent an edge of said shelf constructed and arranged to engage the undersurface of the leading end portion of a wrapper sheet extending downwardly in a substantially vertical plane, movable coacting wrapper clamping rollers adapted to engage the upper surface of said leading end portion of said downwardly extending wrapper sheet and press the same against said driving roller, means for driving said driving roller to move said wrapper sheet a predetermined distance upwardly and advance said leading end portion along said shelf, and thereby reposition the bottom edge of said downwardly extending wrapper relative to an article to be enwrapped therein, and means operative subsequent to the operation of said last-named means for moving said article into engagement with said repositioned sheet.

26. In a wrapping machine of the type having an article lifter table and means for moving said table between an article receiving station and an article delivery station, a wrapper supporting shelf located between said stations and adjacent the path of travel of said table, clamping means carried by said shelf for holding a portion of a wrapper extending downwardly into the path of travel of an article on said lifter table, said last-named means including a driving feed roller mounted adjacent an edge of said shelf constructed and arranged to engage the undersurface of said wrapper sheet, movable coacting wrapper clamping rollers movable into engagement with the upper surface of a wrapper sheet for holding the same against said driving roller, means for driving said driving roller to feed said wrapper sheet a predetermined distance upwardly and along said shelf, means for moving selected clamping rollers away from said driving roller prior to the engagement of an article moving onto said lifter table with said wrapper sheet to control the tension on said wrapper sheet about the article being wrapped.

27. In a wrapping machine of the type having an article lifter table and means for moving said table between an article receiving station and an article delivery station, a wrapper supporting shelf located between said station and adjacent the path of travel of said table, clamping means carried by said shelf for clamping the top portion of a wrapper extending downwardly into the path of travel of an article on said lifter table, said last-named means including a driving feed roller mounted adjacent an edge of said shelf constructed and arranged to engage the undersurface of a wrapped sheet, and movable coacting wrapper clamping rollers adapted to engage the upper surface of a wrapper sheet and press the same against said driving roller; means for driving said driving roller to feed said wrapper sheet a predetermined distance upwardly and along said shelf, means for moving selected clamping rollers away from said driving roller prior to the engagement of an article moving onto said lifter table with said wrapper sheet to control the tension on said wrapper sheet relative to the article being wrapped, a transverse rod, means mounting said rod for movement into and out of engagement with the supports of said clamping rollers, and means carried by said lifter table constructed and arranged to engage said rod and lift said rod for freeing said wrapper sheet from engagement by said rollers.

28. In a wrapping machine of the type provided with an article lifter table, and means for moving said table between an article receiving

station and an article delivery station, means for delivering an article with a wrapper onto said lifter table and partially wrapping said wrapper about said article, means for moving said lifter table with said partially wrapped article to said delivery station wherein a portion of said wrapper extends downwardly beneath said lifter table, wrapper web feeding mechanism mounted on said lifter table, means for driving said mechanism when said lifter table is located at said article delivering station, and means for displacing said downwardly extending portion of said wrapper out of the path of travel of the advancing wrapper web being fed by said mechanism.

29. In a wrapping machine of the type provided with an article lifter table and means for moving said table between an article receiving station and an article delivery station, means for delivering an article with a wrapper onto said lifter table and partially wrapping said wrapper about said article, means for moving said lifter table with said partially wrapped article to said delivery station wherein a portion of said wrapper extends downwardly beneath said lifter table, wrapper web feeding mechanism mounted on said lifter table, means for driving said mechanism while said lifter table is located at said article delivery station, means for displacing said downwardly extending portion of said wrapper out of the path of travel of the advancing wrapper web being fed by said mechanism, a device for receiving the advancing end of said wrapper web and for clamping said end against movement relative to said lifter table whereby as said lifter table moves to article receiving position the web is draped in the path of travel of said article onto said lifter table, and means for cutting said draped portion of said web from said supply to form a wrapper sheet.

30. A paper feeding device for a wrapping machine comprising wrapper gripping means, means for operating said grippers to grip and hold the leading end portion of a wrapper web, means for draping a length of said web in a substantially vertical plane, means for cutting a wrapper of predetermined length from said draped web, and means for moving said gripping means to lift said cut length in a substantially vertical direction upwardly to reposition said draped cut wrapper in the path of travel of an article to be wrapped, said last-named means being constructed and arranged to reposition said wrapper prior to its engagement with an article to be wrapped, and means for moving said article into engagement with said repositioned wrapper.

31. A paper feeding device for a wrapping machine comprising coacting web feeding rollers, means for advancing the leading end of a wrapper between said rollers, means for effecting relative clamping movement between said rollers to grip and hold said advancing end of said wrapper web, means for draping said wrapper in the path of travel of an article to be wrapped, means for cutting a predetermined length from said draped wrapper web, means for driving said feed rollers to feed said cut length vertically and reposition the bottom end portion thereof relative to the path of travel of an article, and means for moving an article against said repositioned sheet to partially enwrap said article therein.

32. A paper feeding device for a wrapping machine comprising coacting web feeding rollers, means for advancing the leading end of a wrapper between said rollers, means for effecting relative clamping movement between said rollers to

grip and hold said advancing end of said wrapper web, means for draping said wrapper in the path of travel of an article to be wrapped, means for cutting a predetermined length from said draped wrapper web, means for driving said feed rollers to lift said cut length vertically and reposition the bottom end portion thereof relative to the path of travel of said article, means for moving said article against said repositioned sheet to partially enwrap said article therein, and means for adjusting the operation of said feeding mechanism for limiting the amount of repositioning movement of said length.

33. A support for a wrapper sheet suspended in the path of travel of an article to be wrapped, a plurality of devices for clamping a top portion of said sheet, means for moving some of said devices out of clamping engagement with said portion of said web prior to the movement of said article against said sheet, and means for moving the remaining clamping devices out of engagement with said web portion when said wrapper is substantially encircled about said article.

34. In a wrapping machine of the type provided with a lifter table adapted to move between an article delivery station and an article receiving station, a wrapper support, an article supporting surface on said lifter table, a web feeding couple mounted on said table beneath said surface, and means for periodically driving said couple to feed a predetermined length of web beneath said surface to deliver a portion of the advancing end of said wrapper onto said support.

35. In a wrapping machine of the type provided with a lifter table adapted to move between an article delivery station and an article receiving station, a wrapper support, an article supporting surface on said lifter table, a web feeding couple mounted on said table beneath said surface, means for periodically driving said couple to feed a predetermined length of web beneath said surface to deliver a portion of the advancing end of said web onto said support, means for cutting a wrapper sheet from said web, and means on said support for feeding an additional portion of said cut sheet along said support.

36. A web feeding mechanism for a wrapping machine comprising a device for pulling web from a reel supply, a pair of feed rolls mounted on a traveling member, means for moving said member up and down between fixed limits, means for operating said pair of feed rolls when said member is positioned at its upper limit of movement, and means for simultaneously operating said device to pull web from said reel and deliver the same to said feed rolls.

37. A web feeding mechanism for a wrapping machine comprising a device for pulling web from a reel supply, a pair of feed rolls mounted on a traveling member, means for moving said member up and down between fixed limits, means for operating said pair of feed rolls when said member is positioned at its upper limit of movement, means for simultaneously operating said device to deliver web pulled from said reel to said feed rolls, and means for stopping the operation of said feed rolls when a predetermined length of paper has been feed therebetween.

38. In a web feeding mechanism for a wrapping machine comprising, a device for pulling web from a reel supply, a slack roller, spaced elongated guides mounting said slack roller, a pair of feed rolls mounted on a traveling member, means moving said member up and down

between fixed limits, means for operating said pair of feed rolls to feed a predetermined length of web when said member is at its upper limit, means for simultaneously operating said device to make available web to be fed by said feed rolls, and means operated by said slack roller for incapacitating said device when a predetermined quantity of slack web has been provided.

39. In a wrapping machine, a support for a wrapper sheet suspended in the path of travel of an article to be enwrapped therein, devices for clamping a portion of said sheet on said support, and means for progressively removing said clamping devices from clamping engagement with said support.

40. In a wrapping machine, a support for a wrapper sheet suspended in the path of travel of an article to be enwrapped therein, a plurality of devices for clamping a portion of said sheet on said support, means for removing selected devices from engagement with said portion of said sheet, and other means operative subsequently for moving other clamping devices from clamping engagement with said sheet.

41. In a wrapping machine, a web holding device, web feeding mechanism for advancing the leading end portion of a web of wrapping material into said holding device, an auxiliary web feeding mechanism for pulling web material from a source of supply for delivery to said first-named mechanism, a movably mounted slack roller located between said first-named web feeding mechanism and said auxiliary web feeding mechanism, means for driving said first-named web feeding mechanism to feed a predetermined length of web to said device, said slack roller being raised during the feeding operation of said first-named web feeding mechanism, means for driving said auxiliary web feeding mechanism to continue the feed of web material from said reel, and means operated by said slack roller for stopping the operation of said auxiliary web feeding mechanism when a predetermined amount of slack has been pulled from said source of supply.

42. In a wrapping machine of the type provided with a lifter table adapted to move between an article delivery station and an article receiving station, a wrapper support, an article supporting surface on said lifter table, a web feeding couple mounted on said table beneath said surface, and means for periodically driving said couple to feed a predetermined length of web beneath said surface, and deliver a portion of the advancing end of said wrapper onto said support.

43. In a wrapping machine of the type provided with a lifter table adapted to move between an article delivery station and an article receiving station, a wrapper support, an article supporting surface on said lifter table, a web feeding couple mounted on said table beneath said surface, means for periodically driving said couple to feed a predetermined length of web beneath said surface, and deliver a portion of the advancing end of said wrapper onto said support, means for cutting a length of material from said web, and means for repositioning said length of material on said support.

44. In a wrapping machine having an article lifter table adapted to be moved to and from an article receiving station and an article delivery station, web feeding mechanism carried by said lifter table, means for driving said mechanism to feed a length of wrapping material relative to said table, a conveyor for delivering articles to be wrapped to said receiving station, and article 70

controlled mechanism for preventing operation of said driving means when an article fails to arrive at said receiving station.

45. A web feeding mechanism for a wrapping machine comprising a device for pulling a web from a source of supply, a traveling article carrying member, web feeding means carried on said member, means for moving said member between an article receiving station and an article delivery station, means for operating said web feeding means when said member is located at said delivery station, means for operating said device to deliver web to said web feeding means, a conveyor for delivering articles to be wrapped to said receiving station, and a control device for preventing the operation of said web feeding means when an article fails to arrive at said receiving station.

46. In a wrapping machine of the type provided with an article lifter table, and means for moving said table between an article receiving station and an article delivery station, a source of supply of wrapper web material, means for delivering an article with a wrapper onto said lifter table and partially wrapping said wrapper about said article, means for moving said lifter table with said partially wrapped article to said delivery station wherein a portion of said wrapper extends downwardly beneath said lifter table, 30 wrapper web feeding mechanism mounted on said lifter table, means for driving said mechanism when said lifter table is located at said article delivering station, an auxiliary web feeding device, mechanism operative while said last-named 35 means is operative for delivering web material from said supply to said web feeding mechanism on said table, and means for displacing said downwardly extending portion of said wrapper out of the path of travel of the advancing wrapper web being fed by said mechanism.

47. In a wrapping machine of the type provided with an article lifter table, and means for moving said table between an article receiving station and an article delivery station, a source of supply of wrapper web material, means for delivering an article with a wrapper onto said lifter table and partially wrapping said wrapper about said article, means for moving said lifter table with said partially wrapped article to said delivery station wherein a portion of said wrapper extends downwardly beneath said lifter table, 50 wrapper web feeding mechanism mounted on said lifter table, means for driving said mechanism when said lifter table is located at said article delivering station, an auxiliary web feeding device, mechanism for operating said device during and after the operation of said last-named means for delivering web from said supply to said web feeding mechanism on said table, means for displacing said downwardly extending portion of said wrapper out of the path of travel of the advancing wrapper web being fed by said mechanism, and a control device for stopping the operation of said auxiliary web feeding device when a predetermined quantity of web material has been pulled from said supply.

48. In a wrapping machine of the type provided with an article lifter table, and means for moving said table between an article receiving station and an article delivery station, means for delivering an article with a wrapper onto said lifter table and partially wrapping said wrapper about said article, means for moving said lifter table with said partially wrapped article to said delivery station wherein a portion of said wrapper 75 extends downwardly beneath said lifter table,

means for feeding the advancing end of a web of wrapping material in a substantially horizontal plane beneath said table, mechanism located beneath said article delivery station for displacing the downwardly extending portion of said wrapper on said article out of the path of movement of said end of said web, means for actuating said mechanism when said lifter table is located at said delivery station, and a conveyor for moving said partially wrapped article off said lifter table.

49. In a wrapping machine of the type provided with an article lifter table, and means for moving said table between an article receiving station and an article delivery station, means for delivering an article with a wrapper onto said lifter table and partially wrapping said wrapper about said article, means for moving said lifter table with said partially wrapped article to said delivery station wherein a portion of said wrapper extends downwardly beneath said lifter table, wrapper web feeding mechanism mounted on said lifter table, means for driving said mechanism when said lifter table is located at said article delivering station, means for displacing said downwardly extending portion of said wrapper out of the path of travel of the advancing wrapper web being fed by said mechanism, and means for controlling the tension of a wrapper encircled about an article.

50. In a wrapping machine of the type provided with a lifter table adapted to move between an article delivery station and an article receiving station, a wrapper support, an article supporting surface on said lifter table, web feeding mechanism mounted on said table beneath said surface, means for periodically driving said mechanism to feed a predetermined length of web beneath said surface to deliver a portion of the advancing end of said web onto said support, means for cutting a wrapper sheet from said web, means for positioning said wrapper sheet in the path of travel of an article onto said table, means on said support for feeding an additional portion of said cut sheet along said support, and means for controlling the tension of said sheet as it is encircled about said article.

51. In a wrapping machine provided with an article lifter table adapted to be moved back and forth between an article receiving and an article delivery station, a source of supply of wrapping material web, a web receiving mechanism located adjacent said delivery station, a web feeding device carried by said lifter table, an auxiliary web feed, means for operating said feed to feed web from said source of supply to said device, and means for driving said device to feed a length of wrapping material to said mechanism.

52. In a wrapping machine of the type provided with an article lifter table, and means for moving said table between an article receiving station and an article delivery station, means for delivering an article with a wrapper onto said lifter table and partially wrapping said wrapper about said article, means for moving said lifter table with said partially wrapped article to said delivery station wherein a portion of said wrapper extends downwardly beneath said lifter table, wrapper web feeding mechanism mounted on said lifter table, means for driving said mechanism when said lifter table is located at said article delivering station, means for displacing said downwardly extending portion of said wrapper out of the path of travel of the advancing wrapper web being fed by said mechanism, opposed relatively movable wrapper holding devices lo-

cated in the path of travel of the end of wrapper web fed by said mechanism, means maintaining said devices separated during the operation of said mechanism, and operative substantially with the movement of said table to article receiving position for causing said holding devices to firmly grip and hold said end of said web.

53. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station wherein a portion of said wrapper extends downwardly beneath said table, wrapper web feeding mechanism mounted on said table, means for driving said mechanism while said table is located at said article delivery station, an auxiliary wrapper web feeding mechanism, means operating said last-named mechanism in timed relation with said wrapper web feeding mechanism for feeding web from a source of supply to said web feeding mechanism, means for displacing said downwardly extending portion of said wrapper out of the path of travel of the advancing wrapper web being fed by said first-named mechanism, a device for receiving the advancing end of said wrapper web, means forming a part of said auxiliary web feeding mechanism for clamping said web end against movement relative to said table whereby as said table moves to article receiving position the web is draped in the path of travel of said article onto said table, and means for cutting said draped portion of said web from said supply to form a wrapper sheet.

54. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station wherein a portion of said wrapper extends downwardly beneath said table, wrapper web feeding mechanism mounted on said table, means for driving said mechanism while said table is located at said article delivery station, an auxiliary wrapper web feeding device, means operating said device in timed relation with said wrapper web feeding means for feeding web from a source of supply to said web feeding means, means for displacing said downwardly extending portion of said wrapper out of the path of travel of the advancing wrapper web being fed by said mechanism, a holding device for receiving the advancing end of said wrapper web, means forming a part of said auxiliary web feeding mechanism for clamping said web end against movement relative to said table whereby as said table moves to article receiving position the web is draped in the path of travel of said article onto said table, means for cutting said draped portion of said web from said supply to form a wrapper sheet, a control mechanism for incapacitating said wrapper web feeding means if an article fails to be delivered to said receiving station for movement onto said table, and means for incapacitating said auxiliary web feeding device when a predetermined quantity of web has been fed from said supply.

55. The method of wrapping which comprises feeding an article into position for association

with a wrapper, feeding the leading end of a wrapper web to a support, holding said web end on said support and draping a length of web in a substantially vertical plane in the path of movement of said article, cutting a predetermined length from said web to form a wrapper, moving said cut draped wrapper upwardly relative to said article at said position to reposition said wrapper in predetermined relationship with said article, and then moving said article from said position against said repositioned wrapper to partially enwrap said article therein.

56. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station wherein a portion of said wrapper extends downwardly beneath said table, wrapper web feeding mechanism mounted on said table, means for driving said mechanism while said table is located at said article delivery station, means for displacing said downwardly extending portion of said wrapper out of the path of travel of the advancing wrapper web being fed by said mechanism, a holding device for receiving the advancing end of said wrapper web and for clamping said web end against movement relative to said table whereby as said table moves to article receiving position the web is draped in the path of travel of said article onto said table, means for cutting said draped portion of said web from said supply to form a wrapper sheet, a folding and sealing chute, means for moving said partially wrapped wrapper from said table at said delivery station through said chute, a delivery conveyor, and means for controlling the speed of movement of said conveyor.

57. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station wherein a portion of said wrapper extends downwardly beneath said table, wrapper web feeding mechanism mounted on said table, means for driving said mechanism while said table is located at said article delivery station, means for displacing said downwardly extending portion of said wrapper out of the path of travel of the advancing wrapper web being fed by said mechanism, a holding device for receiving the advancing end of said wrapper web and for clamping said web end against movement relative to said table whereby as said table moves to article receiving position the web is draped in the path of travel of said article onto said table, means for cutting said draped portion of said web from said supply to form a wrapper sheet, a folding

and sealing chute, means for moving said partially wrapped article from said lifter table through said chute to complete the enwrapment of said article, a conveyor system constructed and arranged to deliver packages from said machine including spaced endless belts, and a bottom belt, means for driving said belts slowly for one size of package, and more rapidly for another size of package.

58. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station, a folding and sealing chute, said chute including means for wrapping and sealing articles of different widths, mechanism for moving said partially wrapped article from said lifter table at said delivery station through said chute to complete the enwrapment of said article, a conveyor system constructed and arranged to deliver packages from said machine, including spaced endless belts and a bottom belt, selective driving mechanism for said belts including means for driving said belts slowly for one width of package and more rapidly for another size of package, and a control member for actuating said mechanism to drive said belts at a selected rate of speed.

59. In a wrapping machine of the type provided with an article conveying table and means for moving said table between an article receiving station and an article delivery station, means for delivering an article with a wrapper onto said table and partially wrapping said wrapper about said article, means for moving said table with said partially wrapped article to said delivery station, a folding and sealing chute, said chute including means for wrapping and sealing articles of different widths, mechanism for moving said partially wrapped article from said lifter table at said delivery station through said chute to complete the enwrapment of said article, a conveyor system constructed and arranged to deliver packages from said machine, including spaced endless belts, and selective driving mechanism for driving said belts slowly for one width of package and more rapidly for another size of package, and a control member for actuating said mechanism to drive said belts at a selected rate of speed.

ROBERT J. BEUTEL.
